UNITED STATES PATENT OFFICE.

DAVID BURNFIELD, OF DENVER, COLORADO.

LOCOMOTIVE HEAD AND SIGNAL LIGHT.

No. 823,392.

Specification of Letters Patent.

Patented June 12, 1906.

Application filed June 19, 1905. Serial No. 285,847.

To all whom it may concern:

Be it known that I, DAVID BURNFIELD, a citizen of the United States, residing in the city and county of Denver and State of Colorado, have invented certain new and useful Improvements in Locomotive Head and Signal Lights; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in locomotive head and signal lights of the class whereby the illuminating device which furnishes the illumination directly in front of the locomotive may also be utilized for the 20 signal-lights necessary on opposite sides of the locomotive.

In my improved construction the ordinary reflector is provided with openings on opposite sides through which the rays of light may 25 pass to the lenses mounted in laterally-located casings or casings located on opposite sides of the main headlight-casing. Tubular reflectors connected with the main reflector are preferably employed, the same increasing in size as they extend outwardly, their outer extremities being located in front 30 of the signal-lenses. Each auxiliary or side casing is provided with a curved slide, whereby the light may be shut off from the lens or 35 the color of the light may be changed by passing a colored glass between the rays from the illuminating device and the ordinary lens.

Having briefly outlined my improved construction, as well as the function it is intended 40 to perform, I will proceed to describe the same in detail, reference being made to the accompanying drawings, in which is illustrated an embodiment thereof.

45 In the drawings, Figure 1 is a section taken on the line 1 1 of Fig. 2. Fig. 2 is a front view of a headlight equipped with my improvements. Fig. 3 is a perspective view in

detail of a slide for controlling the signal-lights.

50

The same reference characters indicate the same parts in all the views.

Let the numeral 5 designate the headlight-casing, 6 the lens, 7 the illuminating device, and 8 the reflector, which is funnel-shaped, 55 being smallest at the rear and increasing in size as it extends outwardly, the diameter of its outer extremity being equal to the diameter of the lens.

To each side of the headlight-casing 5 is attached a casing 9, in which is set a lens 10, so located that rays of light passing at an angle of approximately forty-five degrees to the direction of the train's movement will pass through the said lens. I preferably employ 65 a tubular reflector 12 connected with the reflector 8 on opposite sides and surrounding openings 12^a formed in the main reflector. These reflectors 12 project outwardly toward the lenses 10, as heretofore explained. 70

Slidably mounted in each casing 9 is a curved plate 13, having a depending manipulating part 14 exposed exteriorly, whereby the plate 13 may be moved back and forth at will. This plate 13 contains a colored 75 glass 15, filling an opening formed in the plate and adapted when moved to a position in front of a lens 10 to change the color of the light or the color of the rays passing therethrough. When it is desired to shut off the 80 light completely from the lens 10, the slide 13 is moved so that the opaque part of the plate shall occupy a position directly in front of the lens.

Having thus described my invention, what 85 I claim is—

In a locomotive head and signal light, the combination with the main casing, its lens, the reflector and illuminating device, of auxiliary casings located on opposite sides of and 90 projecting laterally beyond the main casing and communicating with the latter, the auxiliary casings being curved and having lenses located to receive rays from the illuminating device, the main reflector having openings to 95 allow the light to pass from the illuminating

device to the lenses of the auxiliary casings, reflecting-tubes entirely concealed by the main and auxiliary casings, the said tubes surrounding the said openings in the main reflector and being located in line with and between the illuminating device and the auxiliary lenses, and curved slides located in the auxiliary casings and adapted to move to positions in front of the lenses of the auxiliary casings, the said slides having openings pro-

vided with colored transparent material adapted to register with the lenses of the auxiliary casings.

In testimony whereof I affix my signature in presence of two witnesses.

DAVID BURNFIELD.
